WRAPPING TABLE

Walter R. Dobbins, 1224 Raum St. NE., and Louis I. Johnson III, 2410 Hartford St. SE., both of Washington, D.C.

Filed May 1, 1962, Ser. No. 69,951

Term of patent 14 years

(Cl. D80—2)

(Granted under Title 35, U.S. Code (1952), sec. 266)

Des. 197,262

PAGE 2

FIG. 4

FIG. 3

FIG. 1 is a front perspective view taken from one end of a wrapping table embodying our new design;

FIG. 2 is a rear perspective view thereof taken from the end shown in FIG. 1;

FIG. 3 is an elevational view thereof taken from the end opposite that shown in FIGS. 1 and 2; and

FIG. 4 is a top plan view thereof.

The broken line representation in FIG. 1 of components used with or stored in the table are for the purposes of illustration only.

The design described herein may be reproduced and

used by or for the Government for governmental purposes without the payment to us of any royalty thereon.

We claim:

The ornamental design for a wrapping table as shown and described.
